(57) **CLAIM**

The ornamental design for the animal food product, as shown and described.

DESCRIPTION

FIG. 1 is a perspective view of the animal food product according to one embodiment thereof;

FIG. 2 is a side elevation view of the animal food product of FIG. 1;

FIG. 3 is a perspective view of another embodiment of the animal food product;

FIG. 4 is a side elevation view of the animal food product shown in FIG. 3; and,

FIG. 5 is a front (or end-on) view of the animal food product shown in FIGS. 1 through 4, the rear view being a mirror image thereof.
